UNITED STATES PATENT OFFICE.

RANSOM E. GOVE, OF FOND DU LAC, WISCONSIN.

HEATER SUPPORT.

1,427,375.

Specification of Letters Patent. Patented Aug. 29, 1922.

Application filed October 3, 1921. Serial No. 504,932.

To all whom it may concern:

Be it known that I, RANSOM E. Gove, a citizen of the United States, residing at Fond du Lac, in the county of Fond du Lac 5 and State of Wisconsin, have invented certain new and useful Improvements in Heater Supports; and I do declare the following to be a full, clear, and exact description of the invention, such as will enable others skilled 10 in the art to which it appertains to make and use the same.

My invention has for its object to provide an extremely simple and inexpensive, yet a highly efficient means for supporting the 15 well known charcoal heaters in freight cars, refrigerator cars and the like.

With the foregoing in view, the invention resides in the novel subject matter herein-after described and claimed, the descriptive 20 matter being supplemented by the accompanying drawings.

Figure 1 is a side elevation of a portion of a refrigerator car with one of its doors 25 swung open, showing the use of my invention for mounting a heater upon the door.

Figure 2 is a sectional view as indicated by line 2—2 of Fig. 1.

Figure 3 is a horizontal sectional view.

Figure 4 is a plan view of the heater supporting bracket.

Figure 5 is a front elevation of the bracket shown in Figure 4.

Figure 6 is a detail perspective view of a portion of the supporting bracket.

Figure 7 is a plan view of the bracing ring, for the heater.

Figure 8 is an edge view of the ring shown in Fig. 7.

In the drawings above briefly described, 40 the numeral 1 designates a portion of a refrigerating car, provided with a pair of hinged outwardly swinging doors 2. I prefer to attach my improved heater supporting means to one of these doors, so that, 45 when the latter is swung open, the heater will be readily accessible.

The numeral 3 designates a bracket which is detachably mounted on one of the doors 2 to support the weight of an ordinary charcoal or other heater H, while the numeral 50 3^a has reference to a bracing ring spaced above the bracket 3 and also secured detachably to the door, said ring being adapted to surround the upper portion of the heater 55 as shown and thereby securely hold it in position upon the bracket 3.

The bracket 3 includes a pair of horizontal bars 4 having their rear ends bent downwardly at 5 to be detachably mounted on the door 2 or other suitable support, the 60 front ends of said bars being bent upwardly to provide a pair of heater engaging fingers 6. A pair of crossed bars 7 have their end portions extending across the horizontal bars 4 and secured thereto by rivets or the 65 like 8, the outer ends of said bars 7 being bent upwardly at 9 to provide additional heater holding fingers which cooperate with the fingers 6 in properly retaining the heater H upon the bracket. By positioning the bars 7 diagonally as shown most clearly in Fig. 4, not only do they provide for effectively supporting the center of the heater bottom against possible sagging, but they form efficient braces for holding the 70 bars 4 in proper relation with each other and preventing any side whipping of these bars as the car is in motion.

Extending from the horizontal bars 4 to their downwardly turned ends 5, are 80 brace bars 10 whose lower ends turn downwardly, said lower ends and the ends 5 being jointly formed with vertical notches 11 adapted to receive cap screws 12 driven into the door 2. The upper portions of the 85 bar ends 5 are formed with vertical slots 13 and hooks 14 carried by the door are adapted to be passed through said slots and turned downwardly, whereby to secure the bracket 3 detachably to the door. In hot 90 weather, when the use of the heater H is not necessary, the bracket 3 may be readily detached from the door by turning the hook 14 into alinement with the slot 13, moving the upper portion of the bracket outwardly 95 from the door, and then bodily lifting the entire bracket from the cap screws 12.

The ring 3^a is formed of front and rear sections 15 and 16 respectively, said sections being hinged together at one end and having an adjustable overlapping connection 18 at their other ends. A pair of arms 19 are secured to and extend rearwardly from the rear section 16, the rear ends of said arms being bent outwardly at 20 for detachable 100 connection with the door or the like 2. The ring 3 is vertically alined with the heater engaging portion of the bracket 3 and when said ring is clamped around the upper portion of the heater, it will rigidly hold the 110 latter in place upon the bracket.

The invention is simple and inexpensive,

yet has proven to be very effective and in every way desirable, and since excellent results may be obtained from the details disclosed, they are preferably followed. I wish it understood, however, that within the scope of the invention as claimed, numerous minor changes may be made.

I claim:

A supporting bracket for car heaters comprising a pair of parallel horizontal bars 10 rising a pair of parallel horizontal bars bent downwardly at their rear ends for at-

tachment to a support, the front ends of said bars being bent upwardly to form heater holding fingers, and a pair of crossed bars whose end portions extend outwardly 15 across said horizontal bars, said crossed bars being secured to said horizontal bars and having their ends bent upwardly to form additional heater holding fingers.

In testimony whereof I have hereunto set 20 my hand.

RANSOM E. GOVE.
